UNITED STATES PATENT OFFICE.

HENRY J. AUGUSTINE, OF MOORELAND, OKLAHOMA.

HAMMER.

No. 920,518.

Specification of Letters Patent.

Patented May 4, 1909.

Application filed January 2, 1908. Serial No. 408,991.

To all whom it may concern:

Be it known that I, HENRY J. AUGUSTINE, a citizen of the United States, and a resident of Mooreland, in the county of Woodward 5 and State of Oklahoma, have invented a new and Improved Hammer, of which the following is a full, clear, and exact description.

My invention relates to hammers, my more particular purpose being to improve the construction so as to accomplish the following objects: 1. To increase the mobility of the hammer so that the latter may be shifted in a number of independent directions for the purpose of applying it to different portions 15 of work, or readily placing it out of the way a moment after it has been used. 2. To more evenly distribute the weight of the hammer and mechanism immediately connected therewith relatively to its support. 20 3. To simplify the general construction and to promote accessibility to the various parts.

Reference is to be had to the accompanying drawings forming a part of this specification, in which drawings like characters of 25 reference indicate like parts throughout the views, and in which—

Figure 1 is a fragmentary side elevation showing the hammer, the carriage for supporting the same, a track supporting the carriage, and the lever and clutch mechanism used for starting and stopping the hammer, this view showing particularly how the hammer is caused to travel in the general direction of the track, and also to swing freely in 30 planes crossing the general directions of said track; Fig. 2 is an enlarged fragmentary section through the carriage and clutch mechanism mounted thereupon, on the line 2—2 of Fig. 4, this view showing how power is applied to the hammer pitman regardless of the position occupied by the carriage; Fig. 3 is an enlarged vertical section upon the line 3—3 of Fig. 1 looking in the direction of the arrow, and showing in full and dotted lines 35 how the hammer is caused to swing horizontally; Fig. 4 is a section upon the line 4—4 of Fig. 2, looking in the direction of the arrow and showing how power is applied from the main driving shaft through the gears to the 40 hammer pitman; and Fig. 5 is an enlarged section through the hammer head, the springs, and links pivotally connected with the hammer pitman, and the hammer head for supporting the hammer, the section being 45 taken on the line 5—5 of Fig. 1.

Mounted upon massive supports 6, 7, are stationary bearings 8, 9, and supported by these bearings is a main shaft 10. A pulley 11 is mounted upon one end of this shaft for the purpose of turning the same, and a belt 12 engages this pulley for the purpose of supplying power to the machine. A pair of U-beams 13 are disposed oppositely to each other, so that the oppositely disposed portions 14 extend toward each other and are 60 capable of serving as tracks. Bearings 15 are connected with the U-beams 13 by the aid of bolts 16. These bearings are loose upon the shaft 10 so as to remain stationary when the shaft is rotated. A carriage frame 70 is provided with upwardly projecting arms 17, the arms having at their upper ends bearings 18, 19, through which the shaft 10 extends loosely.

Mounted rigidly upon the bearings 18, 19 75 and projecting therefrom are stub shafts 20, and revolvably mounted upon these stub shafts are track wheels 21 arranged in pairs, and engaging directly the projecting portions 14 of the U-beams 13, upon which they 80 freely run. A sleeve 22 loosely encircles the shaft 10 and engages the bearing 18, and another sleeve 23 loosely encircles the shaft and engages the bearing 19, said sleeves being merely spacing members. Intermediate 85 them is a bearing sleeve 24 which carries a gear wheel 25, these parts being rigid relatively to each other and adapted to turn as a unit. The shaft 10 is provided with a groove 26 serving as a splineway, and fitting into the latter is a spline 27 which is carried by the sleeve 24. The spline-way extends throughout practically the entire length of the shaft 10 and the carriage 17 is adapted to travel 90 longitudinally of this shaft, so that the gear 95 wheel 25 can be moved almost from one end to the other of said shaft. Disposed below the gear wheel 25 is another gear 28 which meshes with it, this gear being mounted loosely upon a shaft 29. This shaft is supported upon bearings 30, 31 carried by the carriage 17. Connected rigidly with the gear wheel 28 is a clutch member 32 which is loose upon the shaft 29. Another clutch member 33 is keyed rigidly upon the shaft 29, 100 and consequently at all times revolvable therewith. A spring 34 and spider 35 are disposed intermediate the clutch members, the spring normally forcing the clutch members apart, and the spider serving to main- 110

tain the spring in proper relation to the clutch member 33. The clutch member 33 is provided with a neck 36, and encircling the latter is a collar 37. A clutch fork 38 is 5 pivotally connected with this collar and used for shifting the clutch member 33 in the general direction of the length of the shaft 29. Mounted upon the carriage 17 is a bearing 39 which supports a stub shaft 40. This 10 stub shaft and the shaft 29 are connected with a double crank 41. A hammer pitman is shown at 43, and is connected with said double crank by a bearing 42. An aperture 44 is provided within the carriage 17 and 15 through this aperture the hammer pitman 43 extends. For the purpose of forming the aperture, the carriage walls 45 are bent outwardly from each other.

Guide rods 46 are connected rigidly with 20 the carriage 17 and hang therefrom. A bracket 47 is mounted upon the lower end of one of these guide rods, and a post 48 is mounted upon the bracket. Extending outwardly from the post 48 is a horizontal bar 25 49, and pivotally mounted upon the latter is a hand lever 50. A rod 51 connects the hand lever with the clutch fork 38. The operator by grasping the hand lever 50 is enabled to actuate the clutch arm, and thus 30 to throw the clutch member 33 into and out of engagement with the clutch member 32. The operator by grasping both the horizontal bar 49 and hand lever 50 and squeezing the same, after the manner of a shear handle, can 35 exert considerable leverage in performing the movement just mentioned. The other rod 46 is provided at its lower end with a nut 52. Spiral springs 53 encircle the guide rods 46. The hammer head is shown at 54 and is 40 provided with bearings 55 which slidably engage the guide-rods. The spiral springs 53 cushion slightly the down thrust of the hammer head. Mounted upon the guide rods 46 is a slide 56, and supported upon this slide are 45 composite leaf springs 57, shown to better advantage in Fig. 5. Connected with the lower ends of these leaf springs, and also with the hammer head 54 are links 58. Mounted upon the lower end of the hammer 50 head is the hammer face 59 which may be of special toughened steel. It is provided with a boss 60 which is secured to the hammer head 54 by aid of a pin 61, and an anvil is shown at 62.

55 The operation of my device is as follows: Power being applied to the main shaft 10, the operator grasps the hand lever 50 and swings the hammer head directly over the anvil. The hand lever 50 being now manipulated as above described, the clutch member 33 is brought into engagement with the clutch member 32, and power is thus applied 60 to the gear wheel 28, being transmitted therefrom through the crank 41, hammer pitman 43 and springs 57 to the hammer

head. The operator by holding his hand upon the hand lever 50 and horizontal bar 49 may, by merely pushing these parts in the proper direction, cause the carriage 17 to travel in the general direction of the length 70 of the shaft 10, and by a gentle side pressure cause the hammer to swing in planes crossing the general direction of the length of the shaft. It will be noted that in this hammer the spring action for effecting movement of 75 the hammer head does not conflict with the swinging movement of this head, nor does it conflict with the movements of the hammer in a direction parallel with the general direction of the length of the shaft 10. Such being the case, the operator can easily move the hammer head around over the anvil in any direction, for the reason that the hammer head is absolutely free to move in any direction in which it will ordinarily be required to 80 move with reference to the top of the anvil.

It will be further noted that there is nothing in any of the movements of the hammer to interfere at all with the action of the clutch mechanism, this mechanism being 90 always under the immediate control of the operator. He can apply any degree of pressure he desires to the movable clutch member, and consequently can allow any degree of slip he desires to take place between the 95 two clutch members. In doing this he can regulate the force of the blow exerted by the hammer, and this feature is independent of any other regulation for substantially the same general purpose.

One point to which I wish to call attention is the fact that the weight of the hammer and its accompanying parts, and even the weight of the carriage and the fixed and movable mechanism carried by it, are all supported 100 in such manner as to rest at all times upon the bearings 15. It is true that one of these bearings may support more weight than the other, but it is also true that the heavy parts do not rest upon the shaft 10 at a point anywhere near its middle. For instance, suppose the parts described to occupy the position indicated in Fig. 1, the portion of the shaft engaged by the bearing sleeve 24 and the gear wheel 25 carried by it, can have no 110 effect in weighting the middle of the shaft, and thus causing the shaft to sag or to break, or even to operate with any lack of precision. The fact that the carriage 17 and the parts carried by it are supported upon the ends of 110 the shaft 10, the meshing of the gear wheels 25, 28, is not interfered with in the slightest by any sagging of the shaft 10, and a positive drive with a minimum of friction is at all times assured. This feature is of great advantage, especially in instances where the driving shaft 10 is comparatively long, and where it is desirable that the carriage 17 shall be moved throughout practically the 120 entire length of the shaft.

I do not limit myself to any particular materials to be used in the construction of the mechanism above described, but find that steel may be employed throughout. 5 Neither do I limit myself to the particular shape or form of any of the parts described, the scope of my invention being commensurate with my claims.

Having thus described my invention, what 10 I claim as new and desire to secure by Letters Patent is:

1. The combination of a shaft, a track disposed adjacent thereto, a carriage mounted upon said track and movable, relatively 15 thereto, said carriage being provided with an opening, a gear member mounted upon said shaft and movable relatively thereto along with said carriage, a second gear member journaled upon said carriage and meshing with 20 said first-mentioned gear member, a shaft connected with said second-mentioned gear member, a crank connected with said shaft, a pitman engaging said crank and extending through said opening in said carriage, a hammer head, and means for supporting said hammer head upon said pitman.

2. The combination of a revoluble shaft, a track extending parallel with said shaft and resting entirely upon the ends thereof, a carriage mounted upon said track and adapted 30 to travel in the general direction of the length of said shaft, a hammer head carried by said

carriage, and means for transmitting power from said shaft to said hammer head.

3. The combination of a revoluble shaft, a track disposed parallel therewith, a carriage supported upon said track and movable along said shaft, a gear member splined upon said shaft and movable in the general longitudinal direction of said shaft, a clutch 40 mounted upon said carriage and movable bodily therewith along said shaft, a gear member meshing with said first-mentioned gear member and connected with said clutch, a hammer head movable with said carriage, 45 and mechanism connecting said second-mentioned gear member with said hammer head for actuating the latter.

4. The combination of a revoluble shaft, a track mounted directly upon said shaft, a carriage mounted upon said track and depending therefrom, a hammer head depending from said carriage, a clutch connected with said shaft and traveling with said carriage, and mechanism connected with said shaft and with said hammer head for actuating the latter.

In testimony whereof I have signed my name to this specification in the presence of two subscribing witnesses.

HENRY J. AUGUSTINE.
